UNITED STATES PATENT OFFICE.

WILLIAM F. HAGEN, OF MANITOWOC, WISCONSIN.

SPARK-PLUG CLEANER.

1,421,001.

Specification of Letters Patent. Patented June 27, 1922.

Application filed February 10, 1921. Serial No. 443,900.

To all whom it may concern:

Be it known that I, WILLIAM F. HAGEN, a citizen of the United States, and resident of Manitowoc, in the county of Manitowoc 5 and State of Wisconsin, have invented certain new and useful Improvements in Spark-Plug Cleaners; and I do hereby declare that the following is a full, clear, and exact description thereof.

10 My invention refers to cleaners for spark plugs or similar articles, and it has for its object to provide a simple, durable and rapid means for cleaning spark plugs by subjecting their foul parts to a blast of air laden with a predetermined quantity of 15 granulated abrasive material, which material is picked up in the travel of the air current, upon the injective principle.

The arrangement and construction of my 20 device is such that a plug can be quickly adjusted to a hopper containing abrasive material, which hopper has extending above the normal line of abrasive material, a blast nozzle, having ports at or near its lower 25 end communicating with the abrasive material. The nozzle has encased therein an air nipple associated with the ports whereby a jet of the air-laden abrasive material is discharged directly against the foul parts of 30 the plug to effectually remove all carbon deposits or other foreign matter, it being understood that air is supplied to the air nozzle under any predetermined pressure, and varying in quantity under manual control.

35 With the above and other objects in view, the invention consists in certain peculiarities of construction and combination of parts, as are hereinafter set forth with reference to the accompanying drawings and 40 subsequently claimed.

In the drawings,

Figure 1 represents a longitudinal sectional elevation of a cleaner device embodying the features of my invention, the section being indicated by line 1—1 of Figure 2, there being certain parts of this view shown broken away and in full to more clearly illustrate structural features.

Figure 2 is a plan view of the same with 50 parts broken away and in section to more clearly illustrate certain details of construction, and

Figure 3 is a detail cross section through the injector nozzle mechanism, the section 55 being indicated by line 3—3 of Figure 1.

Referring by characters to the drawings,

1 represents a reservoir or hopper provided with a series of vent apertures 2 near its upper end, and terminating with a conical centrally apertured bottom 1'. The mouth 60 of the hopper is provided with a flange 1", which is formed with an annular recess near its periphery for the reception of the upper edge of a separating and storage tank 3. The lower end of the tank 3 constitutes 65 a storage chamber, that is, for the collection of sand or other granulating material, which sand is displaced from the hopper through the vent apertures 2 when the device is in operation.

70 The storage chamber portion of the tank is provided with a gate controlled discharged mouth 4, whereby access is had to the collected sand for the purpose of removing it and recharging the hopper. The upper end 75 of the tank is provided with an air exhaust 4', which port is encased by a deflector hood 5, having burred openings 5' therein, the walls of which burred openings are bent outwardly to form baffle plates, whereby air 80 is free to pass through them, but sand or other ingredients is trapped by the baffle walls and caused to drop, by gravity, into the storage chamber, where it settles undisturbed by the air currents traveling through 85 the tank to the exhaust port.

89 The open mouth of the hopper is tightly closed by a cap 6, which cap is removably secured to the hopper flange 1" by bolts 6" that pass through apertured ears of the cap 90 and receive clamping nuts 7. As shown in Figures 1 and 2 of the drawings, the circular cap 6 is provided with an eccentrically disposed threaded plug receiving aperture 8, this aperture being shown in Figure 1, 95 fitted with any standard type of spark plug A, whereby the assembled plug constitutes a stopper or closure for the aperture. The hopper 1 is circular in cross section, and the aperture in its lower conical end is 100 arranged concentrically with the walls of the hopper, being adapted to receive the shank portion 9' of a blast nozzle 9, which nozzle extends to a point near the mouth of the hopper or above the lower line of the sand or 105 other abrasive material that is supplied in bulk to said hopper.

For convenience in manufacture, the pipe nozzle 9 is formed in sections connected by a coupling thimble 9", as shown. The 110 upper end of the blast nozzle 9 terminates with a centrally discharged orifice that is

formed in a mushroom head 10, the upper face of which head is cupped as shown at 10' to thus constitute a baffle or deflector surface for the spent jet, which is discharged 5 from the orifice, directly against the foul surfaces of the plug parts, constituting the inner walls of the shell, the central porcelain spaced from said walls and the electrode. The air blast nozzle 9 is adjustably 10 secured in the orifice of the hopper bottom 1 by a set screw 11, whereby said blast nozzle can be adjusted up or down slightly to very the space between the spark plug parts to be cleaned and the mouth of the nozzle 15 orifice. The shank 9' of blast nozzle is provided with a series of sand receiving ports 12, which ports communicate with the tapered walls of the hopper bottom and the internal bore of the nozzle, being in 20 clined upwardly or in the same direction, as the flow of air therethrough. The internal bore of the nozzle shank 9' is threaded for the reception of an adjustable air discharge nipple 13, the delivery mouth of 25 which nipple is positioned a predetermined distance beyond the sand or other abrasive intake ports 12.

Owing to the fact that the upper end of the air nipple is restricted with relation to 30 the bore of the nozzle 9, a passage is formed thereabout between the ports 12 and the discharge orifice of the nipple. Hence, when air is delivered through the nipple under pressure, more or less vacuum will be de- 35 veloped about the space therebelow, whereby a suction is created which will cause the sand or other abrasive material to be drawn through the ports 12 and upwardly, so as to commingle with the air, prior to its dis- 40 charge from the orifice in the head 10. Thus the air and sand are thoroughly mixed before they are delivered to the clogged or foul parts of the plug.

The air nozzle, as shown, is capable of ad- 45 justment so as to provide the most efficient results with reference to drawing in a sup- 50 ply of sand from the hopper, these results being varied and determined by the distance from the discharge mouth of the nipple ori- 55 fice with relation to the ports. The air delivery nipple 13 is suitably fitted to a valve control supply pipe 14, which may lead to a storage tank or pump, whereby the air supply, under suitable pressure, is maintained.

From the foregoing description, it will be seen that when it is desired to clean a spark plug, the threaded end of the same is ad- 60 justed to the aperture 8, and owing to the disalignment of said aperture with the head orifice of the nozzle 9, the annular space be- 65 tween the central porcelain of the plug and the internal surface of its shell, is brought in approximate direct alignment with said orifice. The valve controlling air supply

through pipe 14 is then opened slightly so as to discharge a comparatively reduced volume of compressed air from the air nipple 13. Thus, a comparatively greater volume of sand will enter the bore of the 70 nozzle 9 through the ports 12, and the com- mingled air and sand will be discharged forcibly against the internal parts of the plug and its electrodes. This blast will eddy about the parts, so as to thoroughly scrub 75 them and finally be deflected backwardly into the hopper. In their downward course, the returned abrasive current of air will strike the cupped surface of the head 10 and scatter so as to break up the force of 80 the flow materially, whereby the bulk of sand contained in the hopper will not be unduly agitated or displaced.

While the cleaning action of the blast is functioning, the operator, to obtain the best 85 results, will slowly revolve the plug A, one turn with relation to its threaded connec- 90 tion in the aperture part, whereby the direct air blast will progressively impinge against the foul parts of the plug throughout its 95 entire surface. When this rotation is com- 100 pleted, the plug can be removed, and in prac- tice it has been found that the foul parts are practically cleansed to the degree of an unused plug.

During the scrubbing operation, the mixed sand and air will form a vapor under slight pressure in the top of the hopper, and this spent air and a certain percentage of the sand will pass out through the vents 2, to the separating tank 3. In the course of its travel, the air will exhaust to the atmos- 105 phere, through the port 4', and the particles of abrasive material will all be trapped and will gradually settle down into the storage 110 chamber at the bottom of the tank, at which point they can be readily removed, and by disconnecting the cap 6 from the mouth of the hopper this abrasive material can be placed back into the hopper for use, this 115 return of the abrasive material being prac- tically continuous after stipulated runs of the apparatus.

The device herein described has been in practical operation, and under ordinary con- 120 ditions, a spark plug can be thoroughly cleansed in from three to five seconds.

While I have shown and described one exemplification of my invention in all of its details, it is understood that I may vary such details within a fair interpretation, as put upon the claims by the skilled mechanic.

I claim:

1. A cleaning apparatus for spark plugs or the like comprising a vented hopper 125 adapted to receive granulated abrasive ma- 130 terial, a blast nozzle having an apertured discharge head arranged to extend above the normal line of the abrasive material, the nozzle being provided with intake ports 130

communicating with the hopper below the normal line of said abrasive material, a cap for the hopper having a plug receiving aperture therein and positioned in a field of contact with the head orifice of the nozzle, an air discharge nipple extending into the blast nozzle and terminating a predetermined distance beyond the intake portion thereof, and a metal air and abrasive separation tank in communication with the hopper.

2. A cleaning apparatus for spark plugs or the like comprising a vented hopper adapted to receive granulated abrasive material, a blast nozzle having an apertured discharge head arranged to extend above the normal line of the abrasive material, the nozzle being provided with intake ports communicating with the hopper below the normal line of said abrasive material, a cap for the hopper having a plug receiving aperture therein eccentrically disposed with relation to the nozzle orifice, a valve controlled adjustable air discharge nipple extending into the lower end of the blast nozzle and terminating a predetermined distance beyond the intake ports thereof, and

means associated with the hopper vents for collecting abrasive material discharged therefrom.

3. A cleaner for spark plugs or the like comprising a vented hopper arranged to receive a bulk of rectangular abrasive material, a blast nozzle having a discharge orifice surrounded by a mushroom head arranged to extend above the normal line of abrasive material, the blast nozzle being provided with intake ports communicating with the bottom portion of the hopper, a cap for the hopper having a plug receiving orifice therein, the same being eccentrically disposed with relation to the nozzle orifice, a valve controlled discharge nipple extending into the blast nozzle, the nipple terminating a predetermined distance beyond the intake ports thereof, and a tank for encasing the hopper having a trapped air exhaust port and a gate controlled discharge mouth.

In testimony that I claim the foregoing I have hereunto set my hand at Manitowoc, in the county of Manitowoc and State of Wisconsin.

WILLIAM F. HAGEN.
